UNITED STATES PATENT OFFICE.

NICHOLAS LENNARDS, OF HARVARD, ILLINOIS.

FIRE-ESCAPE.

SPECIFICATION forming part of Letters Patent No. 292,828, dated January 22, 1884.

Application filed May 24, 1883. (No model.)

To all whom it may concern:

Be it known that I, NICHOLAS LENNARDS, of the town of Harvard, in the county of McHenry and State of Illinois, have invented a new and useful Improvement in Fire-Escapes, of which the following is a clear and exact description, reference being had to the annexed drawing, forming part of this specification.

My invention relates especially to apparatus employed upon buildings to enable the occupants to escape in case of fire, and has for its object the provision of a device simple and cheap to construct, easy to operate, and which will provide ready means for conveying one or more persons safely to the ground from any story of the building whereon it is employed.

The invention consists of two barrels or rollers secured in supports near the top of the building, extending at right angles to the wall upon each side of a window or thereabove. These barrels or drums are provided each with two ropes wound in opposite directions thereon, the extremity of one rope bearing a weight, the extremity of the other being secured to a basket or car. Pivoted near the outer end of each drum is a brake, the operating-arm whereof is provided with a regulating rope or cord which extends to the ground; and my invention also involves certain other novel and useful combinations or arrangements of parts and peculiarities of construction and operation, all of which will be hereinafter first fully described, and then pointed out in the claims.

The accompanying drawing represents a building whereon my device is employed.

Like letters of reference indicate corresponding parts.

40 A is the wall of a building. B are eyes let into said wall upon each side of a window, C. D are also small eyes let into the wall at a suitable point above eyes B. E are arms extending from eyes B, being removably secured thereto by means of thumb-screws F, and held in place by rods G, running from cross or vertical strips H, at the outer extremity of each arm, to eyes D. I is a cross-bar fitting over the arms E, holding them securely against lateral movement. J are brakes pivoted to pieces H, the longer arm of each brake engaging with a governing-rope, K, extending to or nearly to the ground. L are drums jour-

naled below arms E. M are ropes attached to said drums and bearing counterbalancing-weights N. P are ropes wound upon the drums in an opposite direction to ropes M, the free ends being secured to a car or basket, R, said car being provided with rods n, bearing hooks for engaging with eyes m, affixed to the sidewalk, pavement, or other object upon the ground for holding the car against being pulled up by the weights when empty, and when it is desired to prevent its rising.

When constructed and arranged in accordance with the foregoing description, the device may remain secured upon the exterior of the building or attached to the supports when desired, and when located at a window wherefrom persons are desirous of descending is easily held in place by those upon the ground operating the brake-ropes. As the car descends, the weights are drawn up, and when the occupants of the car have alighted the weights will automatically draw the car up to any desired point.

Having now fully described my invention, what I claim as new therein, and desire to secure by Letters Patent, is—

1. A fire-escape consisting of the two drums supported at right angles to the wall of a building, as set forth, the two ropes wound upon each of said drums in opposite directions, the free end of one rope upon each drum bearing a counterbalancing-weight, and the ends of the other ropes engaging with a basket or car, the movements of said cars being regulated by two independent brakes, substantially as shown and described.

2. In a fire-escape of the character herein specified, the arms E, secured to eyes B and bearing pieces H at their outer extremities, rods G, passing from pieces H to eyes D, and cross-bar I, the whole arranged substantially as shown and described.

3. In a fire-escape, the two drums L, supported at right angles to the wall of a building, ropes M and P, car a, and the two brakes J, operated by means of ropes K, the whole combined and arranged to operate substantially as shown and described.

NICHOLAS LENNARDS.
